UNITED STATES PATENT OFFICE.

GEORGE H. STONE, DECEASED, LATE OF COLORADO SPRINGS, COLORADO, BY MARY H. STONE, ADMINISTRATRIX, OF COLORADO SPRINGS, COLORADO.

INTERNAL-COMBUSTION ENGINE.

1,258,959.

Specification of Letters Patent. Patented Mar. 12, 1918.

Application filed June 27, 1917. Serial No. 177,397.

To all whom it may concern:

Be it known that GEORGE H. STONE, deceased, late a resident of the United States, at Colorado Springs, in the county of El Paso and State of Colorado, has invented certain new and useful Improvements in Internal-Combustion Engines, of which the following is the specification.

This invention relates to internal combustion engines and more particularly to an internal combustion engine provided with steam generating and cylinder cooling means.

One of the main objects of the invention is to provide an engine of simple construction and operation in which the heat generated during the operation of the engine may be utilized to produce steam which may be used for operating a steam engine of suitable construction. A further object is to provide simple and efficient means whereby the heat radiated by the engine cylinder may be used to generate steam, means being also provided whereby the hot exhaust gases may be caused to flow through the water chamber about the cylinder so as to assist in the steam generation. A still further object is to provide means whereby the exhaust gases from the engine cylinder may be used to preheat the feed water for the water chamber and caused to subsequently flow through the water chamber so as to assist in the generating of steam. Further objects will appear from the detailed description.

35 In the drawings:—

Figure 1 is a transverse central vertical sectional view taken through an internal combustion engine of standard construction with a cooling and steam generating means constructed in accordance with my invention applied.

Fig. 2 is a section taken substantially on line 2—2 of Fig. 1.

The engine crank-shaft 1 is rotatably supported in the crank case 2 and is connected by the rod 3 and wrist pin 4 to the piston 5 in the usual manner. Piston 5 operates in the cylinder 6 adjacent the upper end of which is provided the ignition device 7 of a standard type used in low tension circuits. The cylinder 6 is provided with a by-pass 8 having the upper opening 9 and the lower opening 10 communicating directly with the interior of the cylinder. The piston 5 is provided with a passageway or duct 11 in

its head which communicates with an opening 12 through the side of the piston. A suitable intake opening 13^a is provided in the crank-case. On its upward stroke the piston compresses the explosive mixture in the upper end of the cylinder and simultaneously draws a new charge into the lower part of the cylinder and the crank-case. On the explosion stroke the new charge is compressed and flows through the passage 11 of the piston head and the by-pass of the cylinder into the cylinder above the piston, being deflected in an upward direction by the baffle plate 13. The hot gases from the explosion are simultaneously expelled from the cylinder through an exhaust conduit 14. This construction and operation is standard and need not be further described in detail.

The cylinder 6 is provided with a plurality of radiating ribs or fins 6^a. An inner casing 15 is mounted concentric with, and in spaced relation to, cylinder 6. This casing is provided at each end with an outwardly directed annular flange these flanges being secured to the extended flange 16 of the cylinder head 17 and the downwardly and inwardly inclined base plate 18 mounted about the base of the cylinder, respectively, by nut and bolt means, suitable packing rings or gaskets being interposed between the flanges of the casing and the base ring and flange of the cylinder head so as to insure a fluid-tight closure between these elements. An outer casing 19 is mounted concentric with inner casing 15 being provided with upper and lower flanges and secured between the base plate 18 and the flange 16 of cylinder head 17. This outer casing is provided with a cover 20 of asbestos or any other suitable heat insulating material secured in place by the usual straps 21. The cylinder 6 and inner casing 15 coöperate to form a water chamber 22 surrounding the cylinder. The outer casing 19 and inner casing 15 coöperate in a similar manner to provide an exhaust chamber 23. A feed water pipe 24 extends into the exhaust chamber 23 at a point adjacent the upper end thereof and is coiled to form a plurality of superposed convolutions 24^a which are mounted in superposed relation within the exhaust chamber concentric with casing 15, these convolutions extending substantially the full length of the outer casing 19. The lower end of pipe 24 is inserted through

the casing 15 so as to communicate with the water chamber 23, adjacent the lower end thereof, as at 24^a. The feed water which may be forced through pipe 24 by means of 5 the usual pump or the equivalent enters the water chamber after flowing through the convolutions 24^a. During its flow through these convolutions this water is subjected to the action of the heated exhaust gases 10 from the cylinder which are discharged into exhaust chamber 23 adjacent the lower end thereof from the exhaust conduit 14 which extends across the water chamber and through the casing 15, the outer arm of 15 this conduit being directed downwardly for this purpose as shown. The hot exhaust gases as they are discharged into the exhaust chamber rise and flow over and about the convolutions of the feed water pipe thus 20 serving to heat the feed water to a relatively high temperature preliminary to its entrance into the water chamber.

A pipe 25 is mounted in the water chamber being coiled to provide a plurality of 25 superposed convolutions 25^a mounted in superposed relation and concentric with, and closely adjacent, the cylinder 6. This exhaust pipe communicates at its upper end with the exhaust chamber as at 25^b and at 30 its lower end discharges into the atmosphere as at 25^c.

The base plate 18 together with the cylinder head 6 and the inner casing 15 and outer casing 19, forms a unit which may be applied to an internal combustion engine of 35 standard construction. The casings may be easily fitted about a cylinder the base plate 18 being secured to the base flange 6^a of the cylinder by nut and bolt means, a suitable 40 packing ring or gasket being interposed between the cylinder base flange and the base plate. This generating appliance is more particularly intended to be used in connection with stationary internal combustion 45 engines such as marine engines, or other high power engines of comparatively heavy construction. When the engine is in operation, a large per cent. of the heat generated will be readily absorbed by the water 50 contained in water chamber 22. In practice, this water chamber will be substantially three fourths full of water, the water level being at approximately line x-x of Fig. 1 of the drawings. The hot exhaust gases 55 flow through the discharge conduit 14 into the exhaust chamber 23. This chamber is made sufficiently large to permit expansion of these gases so that they will flow comparatively slowly toward the upper end of 60 the exhaust chamber, passing over and about the convolutions of the feed water pipe during their upward movement. As the exhaust gases thus move slowly about the feed water pipe in direct contact therewith the 65 greater part of the heat contained in these

gases will be absorbed by the water in the convolutions 24^a so that this water will be raised to a comparatively high temperature preliminary to its entering into the water chamber, the exhaust gases and the convolutions of the feed water pipe thus acting in the capacity of a preheater. When the exhaust gases reach the upper end of the exhaust chamber they will flow through the convolutions of the exhaust pipe 25 so that 70 the heat contained by these gases after passing over the coils of the feed water pipe will be extracted largely by the water in the water chamber 22, after which the exhaust gases will be discharged into the atmosphere. 75 In practice the lengths of the various pipe coils would be so proportioned that the gases discharged would be at approximately the same temperature as the water in the water chamber, or but a few degrees higher. By 80 thus arranging the water chamber and the exhaust chamber, and the pipe coils contained in these two chambers, by far the greater percentage of the heat generated by the engine during its operation is utilized 85 thus eliminating the great waste of energy attendant upon the use of an internal combustion engine not provided with means whereby the heat generated by the engine may be utilized for generating steam. In 90 addition, this insures that the engine cylinder will be sufficiently cooled to effectually eliminate all danger of premature explosion of the explosive mixture, or injury to the engine from excessive heating. After the 95 engine has been operated for a comparatively short time the water within the water chamber 22 will be heated to a sufficiently high degree to generate steam which will collect in the upper portion of the water 100 chamber, this steam being conducted away by the steam pipe 26 which communicates with the water chamber at the upper end thereof, this steam pipe also communicating with a suitable engine or the equivalent in 105 which the steam generated may be used.

What I claim is:—

1. In internal combustion engines, a cylinder, an inner casing mounted about said cylinder in spaced relation thereto so as to 115 form a water chamber surrounding the cylinder, an outer casing mounted about said inner casing in spaced relation thereto so as to form an exhaust chamber about the inner casing, a feed-water pipe communicating with said water chamber adjacent the lower end thereof and provided with a plurality of superposed convolutions mounted in said exhaust chamber, an exhaust pipe mounted within the water chamber and having a plurality of superposed convolutions, said exhaust pipe communicating at its upper end with said exhaust chamber, and an exhaust conduit communicating with the interior of 120 said cylinder and with the exhaust chamber. 125

2. In internal combustion engines, a cylinder, an inner casing mounted concentric with, and in spaced relation to, the cylinder and coöperating therewith to form an annular water chamber surrounding the cylinder, an outer casing concentric with, and in spaced relation to, said inner casing and coöperating therewith to form an exhaust chamber surrounding said inner casing, a feed-water pipe communicating at its lower end with the water chamber adjacent the lower end thereof and coiled to provide a plurality of superposed convolutions mounted in the exhaust chamber, a coiled exhaust pipe mounted within the water chamber and communicating with the exhaust chamber adjacent the lower end thereof.

- 15

ber at the upper end thereof, at its upper end, and with the atmosphere at its lower end, and an exhaust conduit passed through the water chamber and communicating at 20 one end with the interior of the cylinder, said conduit discharging into the exhaust chamber adjacent the lower end thereof.

In testimony whereof I affix my signature in presence of two witnesses.

GEORGE H. STONE,

By MARY H. STONE,
Administratrix of the estate of George H. Stone, deceased.
